UNITED STATES PATENT OFFICE.

JOSEPH EISENMAN, OF LONDON, ENGLAND.

DESIGN FOR A SAILOR-BOY DOLL.

43,992.

Specification for Design.

Patented May 13, 1913.

Application filed December 23, 1912. Serial No. 738,380. Term of patent 3½ years.

To all whom it may concern:

Be it known that I, JOSEPH EISENMAN, a subject of the King of Great Britain, residing at London, England, have invented a new, original, and ornamental Design for a Sailor-Boy Doll, of which the following is a specification, reference being made to the accompanying drawing, forming part thereof.

The figure is a front view of a sailor boy doll showing my new design.

I claim:

The ornamental design for a sailor boy doll, as shown.

JOSEPH EISENMAN.

Witnesses:

O. J. WORTH,
C. P. LIDDEN.
